UNITED STATES PATENT OFFICE.

GEORGE W. SHOOK, OF JACKSONVILLE, FLORIDA, ASSIGNOR TO WILLIAM S. BARNETT, OF JACKSONVILLE, FLORIDA.

NON-REFILLABLE BOTTLE.

SPECIFICATION forming part of Letters Patent No. 768,912, dated August 30, 1904.

Application filed December 18, 1902. Serial No. 135,168. (No model.)

To all whom it may concern:

Be it known that I, GEORGE W. SHOOK, a citizen of the United States, residing at Jacksonville, in the county of Duval and State of Florida, have invented certain new and useful Improvements in Non-Refillable Bottles, of which the following is a specification.

My invention relates to improvements in valves for non-refillable bottles; and it consists, broadly stated, of the combination, with a float-valve and a weight attached thereto to normally hold the valve in a closed position, of a flexible medium interposed between the weight and valve.

15 The object of my invention is to construct a valve for a non-refillable bottle that absolutely prevents the ingress of air or liquid into the bottle no matter what the position of the bottle may be; and with this and minor 20 objects in view my invention consists of the parts and combination of the parts, as will be hereinafter more fully described.

In the drawings, Figure 1 is a vertical central section of a bottle broken away with my 25 invention shown in position in the neck thereof. Fig. 2 is an enlarged perspective view of my improved valve detached from the bottle. Fig. 3 is a vertical central section of the float-valve in detail. Fig. 4 is a detail 30 sectional view of the valve inverted, parts being broken way; and Fig. 5 is a top plan view of the float-valve.

1 represents the bottle, 2 the cork thereof.

3 is an annular groove in the neck of the 35 bottle.

4 is a perforated cap secured in the neck of the bottle by means of a split ring 5, said cap having a transverse member 6, from which depends a rod 7, said rod being provided with 40 an annular groove 8.

9 is a pin passed through and extending beyond each side of the rod 8.

11 is a disk secured to the lower end of the rod 7, said disk having fluid-openings 12, 45 which are adapted to be closed by flap-hinges 13, the pintle 14 of said hinge being so positioned that the inner end of the flap-valve works in the groove 8.

14^a represents rods depending from and secured to the disk 11, to the lower end of which 50 is secured a hemispherical body 15, having an aperture 16 in its top.

17 is a disk secured to the rods 14^a intermediate the cone-shaped body 15 and the disk 11, said disk 17 being provided with a depending annular flange 18, in the periphery of which is formed an annular groove 19, in which is secured a rubber or other suitable 55 resilient packing 20 of a thickness greater than the depth of said groove. 60

21 is a flap-valve hinged at 22 on top of the disk 17, said valve being provided with a float 23, of cork or other suitable material, secured in any practical manner thereto. 24 is a packing secured in any practical manner around 65 the edge of the valve 21, on the under side thereof, said packing fitting around the opening 25 in the disk 17, as more clearly shown in Fig. 5.

26 is a hook or other suitable device 70 secured to the flap-valve, upon the lower end of which below the valve and depending through the opening 25 is a chain or other flexible medium 27, to the lower end of which is secured by a loose joint a rod 29, which in turn has 75 secured loosely to its lower end a weight 30, shown for purposes of illustration as a ball-weight.

The operation of my improved valve is as follows: The normal position of the parts is 80 that shown in Fig. 1, while the position of the parts when the bottle is held in pouring position is indicated in Fig. 4. It will be noticed that the flap-valve 21 is hinged to the disk 17 in such manner that the pressure of the liquid 85 within the bottle will open it, and the pressure of the liquid will also open the flap-valves 13; but the pin 9 will prevent the flap-valves 13 opening far enough to permit the insertion of a wire or other instrument through the 90 perforations of the cap for the purpose of holding the flap-valve 21 open. We will suppose that the contents of the bottle have been emptied and it is desired to refill the same with inferior material. This is ordinarily attempted by jarring the valves down and hold-

ing the bottle in a horizontal position; but it will be seen that even if the valves in this case are jarred down and the bottle is held in horizontal position the ball-weight 30 will, by reason of its position in its cone, immediately slide to the bottom of the cone, thereby compelling the valve to close, thus preventing ingress of any fluid. This would be accomplished even in the absence of a float.

10 We will now suppose that the next attempt will be made by completely inverting the bottle, so that all of the valves will fall to open position by reason of their own weight, whereupon the bottle may be immersed in the liquid, whereupon the fluid will pass up through the perforated cap, strike the winged valves 13, and if they do not close will pass on until it strikes the main flap-valve 21, and a further immersion of the bottle will cause

15

20 the main flap-valve to be floated up by reason of the cork 23 being attached thereto, and the further the bottle is immersed the tighter the main flap-valve is held on its seat by means of its float 23. This floating action of the valve is permitted by the flexible joint formed by the chain 27 between the valve and its weight, whereby the valve may be closed notwithstanding the weight is not moved. I have provided the rim 24, of cork or similar

25

30 material, on the under face of the main flap-valve to insure a perfect seating of the valve against the admission of fluid or air.

The construction of the main flap-valve and of the weight may be varied at will so long

as the flexible joint is formed between the 35 valve and its weight.

I have applied all of the well-known tests for defeating the offices of non-refillable bottles, among which may be mentioned the well-known heat test, and have practically demonstrated that the construction of valve that I have shown is proof against all of said tests.

Having thus described my invention, the following is what is claimed as new therein:

1. In a device of the character described, 45 the combination with a hinged valve, a float secured to the upper side of said valve, and a packing-ring secured to the lower side of said valve, of a flexible medium depending from the lower side of the valve, a weight suspended from said valve by means of said flexible medium, and a hemispherical body in which said weight operates.

2. In a device of the character described, 55 the combination with a hinged valve, a float secured to the upper side thereof, a packing secured to the under side thereof, of a chain depending from the lower side of said valve, and a weight secured to the lower end of said chain, and a hemispherical body in which 60 said weight is adapted to operate.

In testimony whereof I affix my signature in presence of two witnesses.

GEORGE W. SHOOK.
